(57) **CLAIM**

The ornamental design for a combined wireless charger and power bank, as shown and described.

DESCRIPTION

FIG. 1 is a perspective view of a combined wireless charger and power bank embodying my new design;

FIG. 2 is a another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof;

FIG. 9 is another perspective view thereof, showing the article in an alternate configuration.

FIG. 10 is another perspective view thereof, showing the article in an alternate configuration; and,

FIG. 11 is an enlarged view of the selected portion 11 in FIG.

2.

The broken lines shown in the figures depict portions of the combined wireless charge and power bank that form no part of the claimed design. The dash-dot broken lines in the figures are demarcating enlarged areas and form no part of the claimed design.

1 Claim, 11 Drawing Sheets
